UNITED STATES PATENT OFFICE

RUDOLPH H. DIETERT, OF RIDGEWOOD, NEW JERSEY, ASSIGNOR TO ATLANTIC, GULF AND PACIFIC COMPANY, A CORPORATION OF WEST VIRGINIA

SPUD AND SPUD-POINT

Application filed November 17, 1928. Serial No. 320,031.

This invention relates to spuds employed in dredging operations, and particularly to the pointed member of a spud, known as the spud-point, which by its novel construction, 5 may be readily inserted in mud or other bottom material in which a dredge may be operating, and, when in position, offers greater resistance to movement than do spud-points heretofore employed.

10 In hydraulic dredging it is necessary to pivot the dredge so that during a part of its cycle of operation, it may swing through a predetermined angular distance about a fixed vertical axis. The pivoting means, 15 which are known in the art as spuds, are long cylindrical members each having at its lower end a pointed member known as a spud-point. The spuds extend through openings, known as spud wells, on or in the dredge 20 hull, the said openings being of such size relative to the spud and being so arranged as to permit the dredge to rotate about the spud acting as a fixed vertical axis. It is desirable, 25 of course, to be able to cause the point to penetrate the bottom underlying the body of water in which the dredge is operating by the weight of the spud alone.

In the arrangements of the prior art, the spud-point was a conical shaped member. 30 In the use of such spud-points, difficulty has sometimes been experienced in effecting penetration solely by the weight of the spud.

This invention resides principally in a spud-point consisting of the plurality of 35 pointed fins, the planes of which intersect at the longitudinal axis of the spud-point, which type of spud-point is capable of being more readily inserted in the bottom material than are the spud-points heretofore employed.

A spud-point embodying this invention possesses other desirable characteristics. Not only is it capable of offering greater resistance to movement at right angles to its longitudinal axis than do the spud-points heretofore employed, but also it is capable of offering greater resistance to rotation about its longitudinal axis than a point of the old type for equal penetration.

Furthermore, it has been found that the

use of spud-points, embodying this invention, tends to keep them sharpened as they wear away, thereby ensuring a good entering end for the spud.

Another object of this invention resides in 55 the placing of openings in the spud and spud-point to permit the ingress of water during the lowering of the spud, thereby overcoming the detrimental buoyant effect of the hollow portion of the spud; and also to permit the egress of water from the spud when it is being lifted.

Other objects of this invention will be apparent from the following description when read in connection with the attached 65 drawings, of which Figure 1 shows an assembly of a sectionalized spud having a spud-point embodying this invention; Fig. 2 shows in greater detail, the spud-point and the last section of the spud, the portion to the right 70 of the line Y—Y being a longitudinal section and to the left being a plan view; Fig. 3 is a cross section of a spud-point, having four fins; and Fig. 4 is a cross section through the junction of the spud and the spud-point, 75 showing the webs having openings therein between the adjacent fins.

In Fig. 1, the spud 1 comprises a plurality of sections which are so joined as to form a rigid structure. Connected with the spud 1 is a spud-point 2, which consists of the plurality of fins, such as 3, 4 and 5, tapering to a point at one end of the spud-point. While this spud-point has been shown in combination with a sectionalized tubular 85 spud, it is to be understood that the invention is not so limited since it will be obvious that a spud-point embodying this invention may be employed with any type of spud. The details of the spud-point and the manner in which it is connected with the spud, are shown more clearly in Fig. 2. It will be seen from that figure, that the fins taper in size from the junction of the spud-point with the spud, to the pointed end of the spud-point. The degree of tapering is relatively slight for about one-third the distance from the said junction to the pointed end of the spud-point; and throughout the remaining 95 two-thirds the degree of tapering is much 100

greater. The spud-point shown in Fig. 2 has, at the line A—A, the cross section comprising four fins, as illustrated in Fig. 3. The following dimensions serve to illustrate 5 the proportions to be given to a spud-point embodying this invention that would be ten feet long from the junction with spud to its pointed end:—The width of each fin, that is to say, the distance from the longitudinal 10 axis to the outer edge of the fin at the junction of the spud-point and the spud, would be fifteen inches; the width of the said fin at a distance four feet along the spud-point toward its pointed end, would be fourteen 15 inches; the width of the said fin would taper abruptly from that location to the pointed end of the spud-point, being about two and one-half inches wide close to the latter end and being rounded off in the manner shown 20 in the drawings. It is desirable to make clear that the invention is not limited to a structure having four fins such as is illustrated in Fig. 3, but may have a smaller or larger number.

25 In the form of the invention shown in Fig. 2, the spud-point at the line X—X, is formed with a shoulder against which rests the wall of the tubular spud. The end of the spud-point then projects within the spud and is riveted thereto so as to make a rigid joint. The spud-point is so formed at its upper end near the point where it joins the spud, as to create a web between the adjacent fins. Each web has, therein, an opening which 30 permits the egress of water when the spud is being lifted, which openings are clearly shown in Fig. 4, and designated 8, 9, 10 and 35 11. Furthermore, openings such as 6 and 7, have been placed in that section of the spud adjoining the spud-point and close to the junction also to permit the egress of water. Openings similar to 6 and 7 may be placed 40 at a suitable angular distance apart around the end-section of the spud.

45 It is desirable to make clear that the invention is not limited to a spud-point having a particular number of fins, or to one having a particular degree of tapering because those factors may be varied widely without departing from the scope of the invention.

50 While the invention has been disclosed as embodied in a particular form, it is to be understood that it is capable of embodiment in other and different forms without departing from the spirit and scope of the appended 55 claims.

What is claimed is:

1. A spud-point comprising a plurality of fins, the planes of which intersect at the 60 longitudinal axis of the said spud-point, the said fins tapering to a point at one end, and the adjacent fins being joined together at the other end of the spud-point by webs each having an opening therein.
- 65 2. The combination with a spud consisting

of a tubular member, having an opening in the wall thereof to permit the inflow and outflow of water of a spud-point connected with one end of said member, the said spud-point comprising a plurality of pointed fins, 70 spaced apart by webs, the said webs having openings therein to permit the flow of water from the said member whenever the latter is being lifted from the water in which it has been submerged.

3. The combination with a spud, consisting of a hollow member having one or more openings in the wall thereof to permit the free inflow and outflow of water, of a spud-point connected with one end of the said member.

4. A spud consisting of a hollow member having one or more openings in the wall thereof to permit the inflow of water to overcome the buoyancy of the spud when being submerged, and to permit the outflow of water whereby the raising of the spud is facilitated.

In testimony whereof, I have signed my name to this specification this 13th day of November 1928.

RUDOLPH H. DIETERT.
